(No Model.)

H. B. EARECKSON.
TRAP.

No. 424,188.

Patented Mar. 25, 1890.

UNITED STATES PATENT OFFICE.

HENRY B. EARECKSON, OF NEW YORK, N. Y.

TRAP.

SPECIFICATION forming part of Letters Patent No. 424,188, dated March 25, 1890.

Application filed May 23, 1889. Serial No. 311,867. (No model.)

To all whom it may concern:

Be it known that I, HENRY B. EARECKSON, of the city, county, and State of New York, have invented a new and Improved Trap, of which the following is a full, clear, and exact description.

The invention relates to traps for sinks, bath-tubs, laundry-tubs, &c.; and the object is to provide a new and improved trap, which is simple and durable in construction and very effective in operation, for discharging the refuse water, at the same time preventing any gas arising from the discharge from entering the building.

15 The invention consists of certain parts and details and combinations of the same, as will be hereinafter fully described, and then pointed out in the claims.

Reference is to be had to the accompanying drawings, forming a part of this specification, in which similar letters of reference indicate corresponding parts in all the figures.

Figure 1 is a sectional side elevation of the improvement. Fig. 2 is a sectional plan view 25 of the same on the line *x x* of Fig. 1, one of the glazed caps being removed; and Fig. 3 is a perspective view of a clip for holding the valve in place.

The improved trap A is provided with an 30 inlet-pipe B, connected in the usual manner with a sink, bath-tub, laundry-tub, &c., and into the said pipe B leads an overflow-pipe C, also connected in the usual manner with the overflow of the article to which the inlet-pipe B is connected. The latter is provided 35 with a sidewise-extending bend B', forming the lower end, the outer edge of which is slightly inclined, as is plainly shown in Fig. 1.

The bent end B' of the inlet-pipe B passes 40 through an aperture in the end D' of an S-pipe D, having its other end D² inclined downward and extending into the discharge-pipe E, leading to the sewer or cesspool.

On the outer inclined end B² of the bend 45 B' is held an outwardly-opening valve F, provided at its upper end with a lug F', pivoted on a bolt G' of the clip G, held on a rubber ring H, surrounding the end of the bend B', extending into the end D' of the S-pipe D. 50 The outer edge of the rubber ring H extends slightly beyond the inclined edge B² of the bend B' and forms the seat for the valve F.

The latter is inclined at the same angle as the edge B², so that the valve is self-closing. The outer edge of the end D' of the S-pipe 55 D is similarly inclined, and is held closed by a valve I, similar in construction to the valve F, being provided with a lug I', fulcrumed on a bolt G² of a clip G³, similar to the clip G, and held on a rubber ring H', surrounding 60 that part of the end D² extending into the discharge-pipe E. The rubber ring H' forms the seat for the valve I, which latter, on account of being inclined as shown in Fig. 1, is self-closing. 65

The distance that the bend B' passes into the end D' of the S-pipe D is limited by an annular offset B³, formed on the exterior of the bend B', said annular offset B³ abutting against the outside of the end D' of the S-pipe 70 D. In a similar manner an annular offset D³ is formed on the end D² of the S-pipe D, said offset abutting against the outside of the discharge-pipe E. In order to fasten the inlet-pipe B, the S-pipe D, and the discharge-pipe E together, I prefer to use solder J, placed 75 between the pipes B and D and between the pipes D and E, as is plainly shown in Fig. 1.

Into the end D' of the S-pipe D leads a fresh-air-inlet pipe K, directly opposite the 80 valve F. A foul-air-outlet pipe L extends from the upper end of the discharge-pipe E and serves to carry off the foul air and gases arising in the discharge-pipe. The top of the end D' of the S-pipe D is closed by a screw-cap 85 N, provided in its middle with a glass cover O, which permits of examining the workings of the valve F without removing any of the parts. A similar screw-cap P is held on top of the discharge-pipe E, and is also provided 90 with a glass cover Q for examining the workings of the valve I.

The operation is as follows: The discharge-water passing into the inlet-pipe B or the overflow-pipe C, leading to the said inlet-pipe 95 B, flows into the bent end B', and by its pressure opens the valve F, so that the water flows into the S-pipe D. In the latter is formed the seal shown in dotted lines in Fig. 1 at a', so that the discharge-water passes through 100 the bent part of the S-pipe D into the downwardly-inclined end D², and by its pressure opens the valve I and flows into the discharge-pipe E. The moment the water discharged

into the inlet-pipe B has passed through its bend B' the valve F again closes by its own weight, and in a similar manner the valve I closes after the discharge has passed into the discharge-pipe E. As the pipe K, leading into the end D' of the S-pipe D, is connected with the fresh-air inlet, fresh air remains in the upper end of the pipe D. Foul air and gases arising in the discharge-pipe E cannot 5 pass into the S-pipe D, as the said pipe is closed by the valve I. The foul air and gases, however, pass upward from the discharge-pipe E into the foul-air-outlet pipe L, which extends upward, usually above the building 10 in which the trap is used.

In the lower bent end of the S-pipe D is screwed a screw-plug R, serving to conveniently clean said pipe D in case of its being clogged. It will further be seen that the 15 workings of the valves F and I can at all times be conveniently observed through the glass-covered caps N and P.

As the inlet-pipe B is closed by the valve F and the end D' of the S-pipe D is connected 20 with the fresh air by the pipe K, no foul air of any description can pass into the pipe B and into the building.

Having thus fully described my invention, I claim as new and desire to secure by Letters Patent—

1. A trap consisting of an inlet-pipe B, having its lower end B' bent outward and provided with a valve, the pipe D, having a vertical member D', into the inner side of which said valved end B' enters, the pipe D being 35 curved inward and upward under the end B' and provided with an inclined discharge end D², having a valve I, the pipe E, into the side of which the valved end D² enters, ventilating-pipes K L in the pipes D E in front of the 40 valves F I, respectively, and the removable caps on the upper ends of the pipes D E over said valves, substantially as set forth.

2. A trap comprising an inlet-pipe having on its lower end a self-closing valve, an S-pipe 45 into one end of which discharges the said inlet-pipe, a self-closing valve held on the end of the said S-pipe, a fresh-air-inlet pipe opening into the inlet end of the said pipe, a discharge-pipe into which opens the valve of the 50 said S-pipe, a foul-air-outlet pipe leading upwardly from the said discharge-pipe, and glazed caps held on the inlet end of the said S-pipe and on the upper end of the said discharge-pipe, substantially as shown and described.

HENRY B. EARECKSON.
